AXEL WEYDELL, OF INDIANAPOLIS, INDIANA, ASSIGNOR, BY MESNE ASSIGNMENTS,
TO HOUDAILLE-HERSHEY CORPORATION, A CORPORATION OF MICHIGAN

SELF-LUBRICATING FAN

Application filed December 16, 1927. Serial No. 240,519.

This invention relates to a novel fan construction of the general type employed in connection with automobile engines and is directed more particularly to the problem 5 of providing dependable automatic lubrication therefor.

The primary object of my invention is to provide a fan structure embodying a force feed lubricating mechanism operated by the 10 rotation of the fan.

Other objects relate to features of construction and design conducive of simplicity and cheapness of manufacture.

Illustrated embodiments of my invention 15 are found in the accompanying drawings wherein,

Figure 1 is a longitudinal sectional view of a fan constructed in accordance with my invention,

20 Fig. 2 is an end view thereof with the fan spider removed to better illustrate the construction of the pump.

Fig. 3 is a view similar to Fig. 1 of a further embodiment of my invention, and

25 Fig. 4 is a view similar to Fig. 2 illustrating said further embodiment.

In accordance with conventional practice, 30 my novel fan construction is journaled upon a stationary or fixed spindle 1. The body of the fan supporting structure comprises an elongated sleeve 2 having at one end thereof a radially extending flange 3. My invention is directed primarily to the problem of efficiently lubricating the bearing surfaces of 35 the spindle 1 and the elongated sleeve 2. On the outer face of the flange 3 is mounted a fan spider 4 which, as herein shown, is in the form of a plate or disc having radially extending and angularly disposed arms 4' 40 whereon the fan blades 5 may be mounted in any suitable manner. The fan spider may be bolted or otherwise secured to the end face of the flange 3 and the joint between them may be provided with packing of any approved type.

Surrounding the spindle 1 and secured to the rear face of the flange 3 is a cylindrical lubricant containing casing 6. This casing is preferably bolted to the face of the flange 50 and the joint thus formed is provided with a

suitable packing to prevent the leakage of lubricant. At its rear end this casing closely surrounds the spindle and is provided at this point with suitable packing 20. Formed in the forward face of the flange 3 is a recess of substantial depth wherein I locate my novel lubricant pumping construction. This recessed flange, together with the central portion of the fan spider 4 cooperate to provide an oil tight annular lubricant chamber. Located within this chamber and secured to the spindle, is a pump casting 10 wherein is mounted a reciprocable, spring pressed pump plunger 11. The inner peripheral wall of the recess is located eccentric with respect to the axis of the spindle and thus provides an eccentric track or raceway whereon the outer end of the pump plunger 11 is adapted to bear and by means of which this plunger is reciprocated by the rotation of the fan. The motive force for impelling the plunger outwardly is furnished in the form of a spring 12 located between the inner end of the plunger and the bottom of the plunger board. 60 A check valve controlled discharge port 15 is formed in the pump casting and leads to an annular recess 16 formed in the sleeve 2 adjacent the bearing surface thereof with the spindle 1. This discharge port is controlled by a ball or other suitable type of check valve 13. The lubricant is drawn into the pump through the inlet port 14 and is forced thereby to the bearing surfaces above mentioned. The pump casting fulfills the function of a thrust washer by reason of substantially filling the space between the end of hub 2 and the fan spider 4. In this manner the longitudinal thrust in the fan structure in one direction is taken by the face of the pump casting adjacent the end face of the sleeve and in the other direction is taken by the plain face of the pump casting adjacent the inner surface of the fan spider. The housing 6 is adapted to contain a supply of lubricant and is further adapted to discharge lubricant from this supply through the port 8 in the flange 3 and into the recess 9 formed by the flange and the fan spider.

65 A pulley or other suitable driving means may be formed or mounted on the housing 6

for operating the fan to which it is secured. A filler plug of any suitable type may be mounted in this lubricant casing. In order to prevent the leakage of lubricant around the spindle 1 at the point where it passes through the end of casing 6, a spirally arranged groove is formed in the inner surface of the sleeve 2 and so directed that lubricant is fed from adjacent the packing 20 forwardly of the spindle and is discharged through the radial apertures 19 of the sleeve.

In operation, a supply of lubricant having been placed within the casing 6, and the casing rotated by any suitable means, such lubricant will assume the form of an annular layer around the inner periphery of the casing and a portion thereof will be discharged centrifugally through the port 8 and into the chamber 9. From this chamber the lubricant thus furnished will be taken in by the pump and forced through the discharge port 15 to the bearing surfaces of the sleeve 2 and spindle 1. By means of this construction the lubrication of the bearing surface of the fan is automatically and positively provided for.

It will be understood that a plurality of pumping elements may be provided in the chamber 9. Thus, as shown in Figs. 3 and 4, a casting 10' may be substituted for the casting 10, said casting comprising two diametrically opposed parts, each of which is provided with a bore which contains a spring pressed pump plunger 11'. The elements associated with said plungers are similar to the elements described in connection with the modification already described and are identified by the same numerals with the addition of primes thereto. It will be readily understood that the operation of each of the pumping elements is identical with that previously described, with the exception that an increased amount of lubricant is supplied to the bearing surfaces in consequence of the duplication of the pumping elements.

The herein described embodiments of my invention are but two of many forms in which the fundamental features of my invention might be carried into effect. I therefore contemplate such changes as fall within the scope of mechanical skill and within the range of equivalents. For example, the pump casting 10 instead of being secured to the fixed spindle 1, might be secured to or formed as a part of the radial flange 3, in which case the eccentric track or raceway could be provided on the spindle. This would simply be a reversal of the relationship of parts as shown in the drawings.

Having described one form of my invention and the best manner in which it may be carried into effect, what I claim is:

1. In a device of the character described, the combination with a fixed spindle, of an elongated sleeve rotatably mounted on said

spindle, a radially extending circular flange integral with one end of said sleeve, a cylindrical lubricant chamber enclosing said spindle and sleeve and secured to one face of said flange, the opposite face of said flange being provided with an eccentrically disposed recess and having a fan spider secured thereto to constitute a second lubricant chamber, means for centrifugally discharging lubricant from the first said chamber into the second said chamber, a pump casting located in said second chamber and secured to said spindle, said casting having a radial bore, a reciprocating spring pressed plunger disposed in said bore and having engagement at its outer end with the inner periphery of the eccentrically disposed recess, and inlet and discharge parts in said casting, the latter being so disposed as to feed lubricant under pressure to the bearing surfaces of said hub and spindle.

2. In a device of the character described, the combination with a fixed spindle, of a fan structure journaled thereon, said fan structure embodying two communicating lubricant chambers, a reciprocating pump mounted on said spindle and located within one of said chambers and adapted to receive lubricant from the other said chamber and force the same between the bearing surfaces of said fan structure and spindle.

3. In a device of the character described, the combination with a fixed spindle, of a fan structure rotatably mounted thereon, said fan structure embodying two communicating lubricant chambers, the inner peripheral wall of one of said chambers being eccentrically disposed with reference to the axis of said spindle, a pump disposed in said last mentioned chamber and secured to said spindle, said pump embodying a spring pressed reciprocating plunger adapted to bear at its outer end on said eccentrically disposed wall, and ports for receiving lubricant from said chamber and discharging the same to the bearing surfaces of said fan structure and spindle.

4. In a device of the character described, the combination with a fixed spindle, of a fan structure rotatably mounted on said spindle, said fan structure embodying a lubricant chamber, a pump casting carried by one of said elements, an eccentric track carried by the other of said elements and a spring pressed reciprocable plunger mounted in said casting and engaging said eccentric track and a discharge port leading from said pump casting to the bearing surfaces of said fan structure and spindle.

5. In a device of the character described, the combination with a fixed spindle, of a fan structure rotatably mounted on said spindle, said fan structure embodying a lubricant chamber, a pump casting consisting of two diametrically opposed parts carried by one

of said elements, an eccentric track formed on the other of said elements, each of said casting parts having a bore formed therein, a plunger reciprocal in each of said bores and having an end engaging said eccentric track and a discharge port leading from each bore to the bearing surfaces of said fan and spindle.

6. In a device of the character described, the combination with a fixed spindle, of a fan structure rotatably mounted thereon, said fan structure embodying two communicating lubricant chambers, the inner peripheral wall of one of said chambers being eccentrically disposed with reference to the axis of said spindle, a pump disposed in said last mentioned chamber and secured to said spindle, said pump embodying a body portion secured to said spindle and having diametrically opposed bores formed therein, a plunger disposed in each of said bores and having their outer ends in engagement with said eccentric wall, said body portion having inlet and discharge ports therein, the latter being disposed adjacent the bearing surfaces of said fan structure and spindle to supply lubricant thereto and means for urging said plungers outwardly into engagement with said eccentric wall.

7. In a device of the character described, the combination with a fixed spindle, of a fan structure journaled thereon, said fan structure embodying two communicating lubricant chambers, a plurality of reciprocating pumps mounted on said spindle and located within one of said chambers and adapted to receive lubricant from the other said chamber and force the same between the bearing surfaces of said fan structure and spindle.

8. In a device of the character described, the combination with a fixed spindle, of a fan structure rotatably mounted thereon, said fan structure embodying a lubricant chamber, a plurality of pump bores carried by one of said elements, an eccentric track formed on the other of said elements, a plunger receptacle in each of said bores and having an end engaging said eccentric track and a discharge port leading from each bore to the bearing surfaces of said fan and spindle.

In testimony whereof I affix my signature.
AXEL WEYDELL.
